NOSE HAIR CLIPPER

Celestino George D'Ainato, Philadelphia, Pa.

Application August 30, 1948, Serial No. 46,867

5 Claims. (Cl. 30—233)

1

My invention relates to a new and useful nose hair clipper and has for one of its objects to provide a guide on a pair of scissors to limit the distance the points of the scissors may be inserted in a nostril and to provide a rest whereby the scissors will be retained in a relatively steady condition during the cutting operations.

Another object of the invention is to provide a guide for a pair of scissors in an article of the kind mentioned which guide is adapted to be engaged with a person's chin while cutting hairs in the nose to prevent injury to the nose.

Another object of this invention is to provide a nose hair clipper including a pair of scissors and a guide for detachable and interchangeable connection to the shanks of the handles of said pair of scissors.

A further object of the present invention is to provide a nose hair clipper consisting of a pair of scissors having a guide thereon, said guide being adjustable in a direction generally longitudinally of the scissors and angularly in a vertical plane at right angles to the faces of the scissors as well as a substantially horizontal plane.

With the above and other objects in view this invention consists of the details of construction and combination of elements hereinafter set forth and then designated by the claims.

In order that those skilled in the art to which this invention appertains may understand how to make and use the same I will describe its construction in detail referring by numerals to the accompanying drawing forming a part hereof, in which:

Fig. 1 is a view of a person's head and hand with a nose hair clipper in one position of use illustrating how the article is employed.

Fig. 2 is an enlarged face view of the clipper with the guide swung off at an angle.

Fig. 3 is a fragmentary sectional elevation thereof illustrating certain details of construction.

Fig. 4 is a fragmentary edge view of the scissors showing how the outer ends of the blades may be set at an angle to the main parts thereof.

In carrying out my invention as herein embodied 10 represents a pair of scissors including two similar members 11 and 12 pivoted at 13.

Each member 11, 12 includes a handle shank 14 having a finger-piece 15 at the outer or bottom end, both of the finger-pieces being substantially alike so that the scissors may be used in any position, and a blade 16 having the outer or upper end thereof bent at an angle to the main portion

2

to provide an offset tip 17 and the terminal end is made blunt in any suitable manner, as by providing an outwardly extending projection 18.

Each handle shank 14 has a transverse smooth hole 19 therethrough spaced from but adjacent to the pivot 13 for the reception of the threaded neck of the screw-eye hanger 20 which is adjustably held in place by a nut 21 screwed onto the neck and engaged with the inner edge of the handle shank. The eye or head portion of the screw-eye hanger 20 is internally threaded to receive the threaded rod 22 having a head 23 on its lower end. On said lower end of said rod 22 is loosely mounted a guide member 24 so as to rotate and said guide member is held in any circular degree of adjustment by the nut 25 screwed on the rod 22 for clamping the guide member between said rod head 23 and nut 25.

From the foregoing it will be apparent that the guide member 24 may be adjusted in the arc of a circle about the axis of the rod 22, swung into various angular positions in a vertical plane at right angles to the faces of the scissors and moved to and from the blade terminals by screwing said rod in or out of the eye portion of the screw-eye hanger. These adjustments will regulate the parts in such a manner that the blade terminals can only project a limited distance into the nostrils at certain angles in accordance with the measurements and contour of a person's face.

In actual practice, the rod is adjusted longitudinally in the screw-eye hanger until, with the guide member 24 under the chin, the terminals of the blades project the desired distance into a nostril of the person using the clipper. Next,

with the blades in a nostril, the proper pitch of the rod is determined and the nut 21 tightened. Finally the guide member 24 may be rotated to the most convenient location and the nut tightened. After the above adjustments are obtained

the party may then proceed to clip the hairs from one of his own nostrils without the likelihood of injury. If the hairs are at or towards the back of the nostril and the blades have the angular tips 17, the scissors are held so that said angular tips are vertical while at the rear of the nostril, whereas when the hair to be cut is at the front of the nostril the scissors are reversed to bring the angular tips to the vertical position at the front of the nostril.

When the scissors are reversed the guide is adjusted to accommodate the new position of the scissors. After the hair has been cut from one nostril the guide structure is detached from the handle shank on which it was first mounted and transferred to the com-

panion handle shank by removing the nut 21 and withdrawing the screw-eye hanger from the hole in the first handle shank and inserting it in the hole in said companion handle shank and replacing the nut. If necessary, new adjustments of the parts are made before cutting the hairs in the other nostril.

Of course I do not wish to be limited to the exact details of construction herein shown and described as these may be varied within the scope of the appended claims without departing from the spirit of my invention.

Having described my invention what I claim as new and useful is:

1. A nose hair clipper comprising a pair of scissors the handle shanks of which each have a transverse hole therethrough, a hanger selectively mounted in one of said holes and rotatably adjustable, means to hold said hanger in any adjusted position, a rod longitudinally adjustably mounted in said hanger, a guide member rotatably adjustably mounted on the lower end of said rod so as to underlie a person's chin when the cutting end of the scissors is in said person's nostril, and means to hold said guide member in any adjusted position.

2. The nose hair clipper according to claim 1 wherein the tips of the blades of the scissors are at angles to the balance of said blades and the terminals are blunt.

3. The nose hair clipper according to claim 1 wherein the guide member is curved longitudinally.

4. In combination, a pair of scissors including two members pivoted together and each member comprising a blade, a handle shank and a finger-piece, each handle shank having a transverse hole

therethrough spaced a short distance below the pivot point, a screw-eye hanger selectively and rotatably mounted in the hole in one of the handle shanks, the neck of said hanger being externally threaded and the eye internally threaded, a nut on the neck to adjustably and detachably hold the hanger in place, a threaded rod longitudinally adjustable in the eye of said hanger and said rod having a head on its lower end, a guide member loosely mounted on the head end of said rod for rotatable adjustment on said rod, and a nut threaded onto said rod for clamping the guide member against the head in any selected position.

5. In a device of the kind described, a guide structure comprising a hanger to be removably and adjustably attached to the handle shank of a pair of scissors, a threaded rod adjustable longitudinally of itself through a portion of said hanger and having a head at the lower end, a guide member adapted to engage underneath of a person's chin and loosely rotatably mounted on said rod and normally in contact with the head, and a nut on said rod to clamp the guide member in any adjusted position against said head.

CELESTINO GEORGE D'AMATO.
